Inventor

Felix Hartung,
By myself, L. C. Miller,
Attest,

UNITED STATES PATENT OFFICE.

FELIX HARTUNG, OF CHICAGO, ILLINOIS, ASSIGNOR OF ONE-HALF TO THOMAS G. PIHLFELDT, OF CHICAGO, ILLINOIS.

SPRING-OILING DEVICE.

1,332,831.

Specification of Letters Patent.

Patented Mar. 2, 1920.

Application filed May 2, 1919. Serial No. 294,279.

To all whom it may concern:

Be it known that I, FELIX HARTUNG, a citizen of the United States, residing at 4437 North Clark street, Chicago, in the 5 county of Cook and State of Illinois, have invented a new and useful Spring-Oiling Device, of which the following is a specification.

The present invention relates to devices 10 for oiling springs and more particularly to devices whereby oil is applied to the spring in such manner as to seep between the leaves of the spring.

In order that the invention may be clearly 15 understood, an embodiment thereof is hereinafter described and illustrated in the accompanying drawings, in which—

Figure 1 is a side elevation of the device as applied to one end of a spring, for example, a semi-elliptical spring;

Fig. 2 is a longitudinal section therethrough;

Fig. 3 is a transverse section on the line 3—3 of Fig. 1;

Fig. 4 is a bottom view of the upper or top member of the oiling device, and

Fig. 5 is a view from the upper side of the lower or trough member of the device.

In its present embodiment the device is 30 intended for use in connection with force feed oil cups or like mechanism whereby oil is forcibly fed to the shackle bolt bearings of the spring. The present device receives and stores up the excess of oil from 35 the spring bearing and applies it directly to the leaves of the spring, between which it seeps to effect proper lubrication thereof. The present device is furthermore so constructed as to form a protective casing for 40 the end of the spring and to prevent contact of dust, dirt, water, etc., therewith.

Referring more particularly to the drawings, 10 indicates a spring, only one end of which is shown. The spring is constructed 45 in the usual manner of a number of leaves 11—11 of successively increasing lengths, the longest 12 being provided with a loop or eye into which is fitted the bushing 14 for the shackle bolt. A spring clip 15 is 50 provided at a distance from the end of the spring.

The oiling device consists essentially of a trough-like member 16 embracing the bottom and sides of the spring and a cover 55 plate 17. These extend along the spring

from the end to a point near the spring clip 15 and cover the ends of most of the leaves of the spring.

The trough-like member 16 is formed with a bottom 18 and two side members 19, 19. The bottom member 18 is curved upwardly at 20 around the eye 13 of the spring, the side members 19, 19 being cut away to expose the eye. It is provided with a felt lining 21 which extends along the 60 bottom of the trough member 16 and upwardly around the eye of the spring to a point substantially in alignment with a longitudinal diameter thereof, and which also lines the side members 19.

The cover plate 17 is provided with downwardly extending side members 22 which fit over the side member 19 of the trough-member 18. The cover plate 17 likewise extends forwardly over and partially around 70 the eye 13 of the spring at 23, a small piece of felt lining 24 being inserted between the cover plate extension 23 and the spring eye 13. This piece of felt lining extends upwardly to a point substantially 75 opposite the lining 21 of the trough member. The curved extension 23 of the cover plate is fitted underneath the curved extension 20 of the bottom or trough member to protect the spring eye against dust, water, dirt, etc.

To hold the assembled oiling device in position on the spring the cover plate side members 22 are provided with opposite ears 25, through the openings in which are looped 80 the ends of the coiled spring 26 which surrounds the bottom member 16. Any other suitable binding or holding means may obviously be utilized. The device, when assembled, completely surrounds the end of 85 the spring and protects it against the entrance of foreign, injurious material.

The device is preferably utilized with force-feed oil cups, for example, of the type invented jointly by myself and Thos. G. Pihlfeld, and described in application Serial Number 250,406, filed Aug. 17, 1918, the oil cup being applied to the shackle bolts of the spring. The excess of oil passes into the felt linings of the present oiling device, which may, if desired, be previously saturated with oil. The felt lining thus forms 100 a reservoir for the excess oil and applies it to the sides and overlapping ends of the leaves of the spring.

Although I have described my invention 110

in connection with a specific embodiment thereof, it is clearly understood that it is not limited by the details thereof illustrated and described except in so far as such limitations are included in the accompanying claims.

I claim:

1. In a spring oiler, a trough-like member adapted to embrace the sides and bottom of 10 the end of a spring and having a curved extension adapted to embrace a portion of the eye of the spring, a felt lining for said member and extension, and a cover plate covering the top of the spring and the 15 trough-like member.
2. In a spring oiler, a trough-like member adapted to embrace the sides and bottom of 20 the end of a spring and having a curved extension adapted to embrace a portion of the eye of the spring, a felt lining

for said member and extension, and a cover plate covering the top of the spring and the trough-like member and having a curved extension extending over the eye of the spring and coöperating with the extension of the 25 trough-like member to cover the eye of the spring.

3. A spring protector comprising a casing adapted to embrace the sides and bottom of the spring and having a curved extension 30 adapted to embrace a portion of the eye of the spring, a cover plate adapted to cover the top of the spring and the casing, said plate having a curved extension adapted to embrace the remaining portion of the eye of 35 the spring, the extension of the cover plate passing under the extension of the casing, and means for holding the casing and cover plate in assembled position on the spring.

FELIX HARTUNG.
